UNITED STATES PATENT OFFICE.

PETER THOMSEN, OF CASSEL-WILHELMSHÖHE, GERMANY, ASSIGNOR TO SCHMIDT'SCHE HEISSDAMPF-GESELLSCHAFT M. B. H., OF CASSEL-WILHELMSHÖHE, GERMANY, A CORPORATION OF GERMANY.

SMOKE-TUBE SUPERHEATER.

1,116,646.

Specification of Letters Patent. Patented Nov. 10, 1914

Application filed August 21, 1913. Serial No. 785,828.

To all whom it may concern:

Be it known that I, PETER THOMSEN, a subject of the King of Prussia, Emperor of Germany, residing at Cassel-Wilhelmshöhe, 5 Germany, have invented a certain new and useful Improvement in Smoke-Tube Superheaters, of which the following is a specification.

My invention relates to steam superheaters 10 which are known as the smoke tube type and is particularly applicable to such superheaters when used in connection with steam locomotives.

My invention relates particularly to the 15 arrangement of the ends of the superheater elements as they come out of the flue tubes and go to the superheater headers. In superheaters of this type it is usual to arrange the superheater elements in a plurality of 20 rows of flue or smoke tubes and to carry the ends of said elements either up or down, to the right or to the left, to the superheater headers with which they must be connected. In some cases, instead of carrying all of the 25 ends in the same direction, the saturated ends have been carried in one direction to a suitable saturated header, while the superheated ends have been carried in the opposite direction to the superheated header. In 30 superheaters arranged as just described, the ends of the several elements usually cover one another, as viewed from the front of the boiler, so that while each individual element may be removed, the elements may only be 35 removed in a certain definite order. To remove the last element of a certain row, that is the element whose ends lie nearest the tube, it is, therefore, necessary to first remove every other element of said row.

40 It is the object of the present invention to diminish this difficulty.

The invention accomplishes the specified object by arranging the superheater elements belonging to each row of flue tubes in two 45 groups the ends of which are so carried to the header that the ends of one group leave toward one side of the row, while the ends of the other group leave toward the other side of the row. In accomplishing this the 50 ends of the elements are so bent that any element of one group may be removed from the flue tubes without disturbing any element of the other group. As a consequence

of this arrangement the several elements of a given row are no longer dependent upon 55 one another but only dependent upon the elements of the particular group to which it belongs. In a row having four elements, therefore, it is never necessary to disturb more than one other element in order to remove a given element.

The arrangement of this invention is especially applicable to such superheaters as have their elements in enlarged flue tubes which are usually made to contain four 65 lengths of superheater tubes side by side. In superheaters so arranged, the ends of the elements may be conveniently connected directly to the steam headers by means of screws or flanges, so that an individual element is very easily removed. But even in superheaters having the elements in flue tubes of normal diameter, this invention serves a very useful purpose. In such superheaters it would be difficult to connect the 75 element ends to the steam headers by reason of the lack of sufficient space for screws and flanges or other connecting devices. It is possible, however, when small flue tubes are used, to carry the superheater element ends 80 to intermediate steam chambers or sub-headers which themselves are directly fastened to the main steam headers. Or, the ends of the small tube superheater elements may be joined directly to the main steam 85 headers by expanding, welding or in some equivalent manner.

My invention will be better understood with reference to the drawings in which—

Figure 1 represents an elevation taken 90 from the front of part of a boiler embodying one form of my invention; Fig. 2 represents a part elevation taken along the line 2—2 of Fig. 1; Fig. 3 represents a view, similar to Fig. 1, showing another embodiment of 95 my invention and Fig. 4 a view, similar to Fig. 2, taken along the line 4—4 of Fig. 3; Fig. 5 represents a view, similar to Fig. 1, showing a third embodiment of my invention and Fig. 6 a view similar to Fig. 2 taken 100 along the line 6—6 of Fig. 5; Fig. 7 represents a view similar to Fig. 1 showing a fourth embodiment of my invention and Fig. 8 a view similar to Fig. 2 taken along the line 8—8 of Fig. 7; Fig. 9 represents a view 105 similar to Fig. 1 showing a fifth embodi-

ment of my invention and Fig. 10 a view similar to Fig. 2 taken along the line 10—10 of Fig. 9; Fig. 11 represents a view similar to Fig. 1 showing a modification of my invention in which two rows of flue tubes 5 take the place of one row of the earlier embodiments, and in which each superheater element lies in two tubes, one belonging to one row of flue tubes and the other belonging to an adjacent row of flue tubes; Fig. 12 represents a view similar to Fig. 2 taken along the line 12—12 of Fig. 11; Fig. 13 represents a view similar to Fig. 1 showing still another modification of my invention 15 and Fig. 14 a view similar to Fig. 2 taken along the line 14—14 of Fig. 13.

Referring to the drawings, (Figs. 1, 2) the saturated and superheated headers *a* and *b* lie respectively above and below the vertical row of superheater elements and transversely thereto. The flue tubes of this row are designated respectively as *c*, *c'*, *d* and *d'*, *c* and *c'* each containing a single superheater element *e* and *e'* respectively, and *d* and *d'* 20 each containing a single superheater element *f* and *f'* respectively. The elements *e* and *e'* belong to one group and the elements *f* and *f'* to another group. In this arrangement it will be noticed that the two ends 25 of the uppermost superheater elements *e* are carried to the left of the row, one end *g* going up to the saturated header *a* and the other end *g'* down to the saturated header *b*. The ends *h* and *h'* of the other element *e'* 30 belonging to this group are also carried to the left, but behind the ends *g* and *g'* of the element *e*, and go up and down respectively to the saturated and superheated headers. Similarly, the elements *f* and *f'* have their 35 ends carried to the right of the row and extend up and down to the headers, the ends of one element lying behind the ends of the other element. The elements *e* or *f* may be instantly removed as soon as the connecting 40 means binding them to the headers is released, while elements *e'* or *f'* may be removed similarly by first removing either *e* or element *f'* as the case may be. In this modification each element comprises four 45 parallel lengths of superheater tube contained in a single flue tube.

In the modification shown in Figs. 3 and 4 each element comprises four lengths of superheater tube, two lengths in one flue 50 tube and two lengths in an adjacent flue tube. Another similar element also has two lengths in one of these flue tubes and two lengths in the other flue tube. Thus each flue tube contains as before, four superheater 55 element lengths, two lengths belonging to one element and two lengths belonging to another element. In this modification the element *e* has two of its lengths, in the upper flue tube and its other two lengths in the 60 next lower flue tube the upper end being 65

carried to the right and up to the saturated header *a* and the lower end being carried to the right and down to the superheated header *b*. The other element of the group, *e'*, has two of its lengths on the right of 70 the third flue tube and two of its lengths on the right of the bottom flue tube, the upper end being carried to the right and up to the saturated header *a*, and the lower end to the right and down to the superheated 75 header *b*, but both upper and lower ends lying behind the corresponding ends of element *e*. In the same way the elements *f* and *f'* lie respectively in the top two and the bottom two flue tubes on the left of the row 80 with their ends carried out to the left and up and down to the headers, one set of ends behind the other.

In the modification shown in Figs. 5 and 6, the row contains but three tubes, each 85 containing four lengths of superheater pipe belonging to a single element. The two upper flue tubes contain respectively the two elements *e* and *e'* of one group, while the bottom flue tube contains the element *f* 90 which is the only element of the other group. The ends of elements *e* and *e'* belonging to one group are carried to the left and up and down respectively and in front of one another as are the elements *e* and *e'* of Figs. 1 95 and 2, while the ends of the element *f* are turned around to the right and up and down. The element *f* has clearly nothing to interfere with its removal and as to the elements *e* and *e'*, the latter can be interfered with only by element *e* and may be removed after first removing said element. 100

In the arrangement shown in Figs. 7 and 8 both headers *a* and *b* are arranged above the row, the upper two flue tubes containing 105 the two elements *e* and *e'* belonging to one group, and the other flue tubes the elements *f* and *f'* belonging to the other group. Each element comprises four tube lengths, two of 110 said lengths lying in one flue tube and two in the adjacent flue tube.

Referring to Figs. 9 and 10 both headers here as in the previous modifications comprise four tube lengths. The upper two flue tubes contain two elements of two groups, the element *e'* lying on the left with two of its 115 lengths in the top tube and two of its lengths in the next lower tube, while the element *f'* lies similarly on the right. The third flue tube contains the four lengths of the element *e* and the fourth of the tube contains the four lengths of the element *f*. The ends of each element lie in a single plane but these planes are all different to one another so that the ends of no one element lie in front of the ends of any other element. Any element, therefore, may be removed without interference with any other element of either group. 125

In the arrangement shown in Figs. 11 and 130

12 the two headers are again, as in the earlier modifications, arranged respectively above and below the double row of flue tubes. It should be noted that in this arrangement, two sets of vertically disposed flue tubes of a double row are staggered relatively to one another. Each element as, in all the other modifications, has four tube lengths, but in this arrangement two lengths 5 lie in a tube on one side of the double row, while the other two lengths lie in the lower tube on the other side of the double row. The pairs of flue tubes belonging to the individual units may be designated as 1, 2, 3 10 and 4. The element e has two lengths in each tube of pair 1, the two ends being carried respectively right and left and up and down to the two headers. The element e' lies in the set of flue tubes 2, with its ends 15 respectively behind the ends of the element e and going to the headers similarly. Elements f and f' are arranged respectively in the sets of flue tubes 3 and 4, the end of said elements being respectively behind one another and extended to the right and left and up and down, but to the left and right respectively of the corresponding ends of 20 elements e and e' .

In the modification shown in Figs. 13 and 30 there are 8 flue tubes in a row, these flue tubes being assumed to be normal diametered tubes so that each tube is capable of containing only two lengths of superheater elements, each element however comprises 35 four lengths of superheater tube as before so that each element is disposed in each of two flue tubes, two lengths lying in one flue tube and the other two lengths lying in the next adjacent tube. The flue tubes may be 40 designated as 5 to 8 inclusive. The upper four flue tubes contain the two elements e and e' of one group while the lower four flue tubes contain the two elements f and f' of the other group. The ends of the elements of each group lie behind one another 45 and are extended to the left and right respectively and up and down to the headers. No individual element may be removed without at the same time removing the other 50 element of the group, but no element of one group interferes in any way with an element of another group.

Having described my invention, I claim:

1. A smoke tube superheater comprising, 55 in combination, a boiler provided with parallel rows of smoke tubes, sets of superheater elements at least three to a set arranged in rows corresponding to smoke tube rows, and steam collectors for saturated and 60 superheated steam respectively, the ends of the superheater elements being joined to said collectors and all the said elements of a given set having their ends arranged in one or the other of two groups and in dif- 65 ferent planes parallel to the smoke tube

rows so that any element of a given group may be inserted or removed without interfering with any element of another group.

2. A smoke tube superheater comprising, 70 in combination, a boiler provided with parallel rows of smoke tubes, sets of superheater elements at least three to a set arranged in rows corresponding to smoke tube rows, and steam collectors for saturated and superheated steam respectively, the end of 75 the superheater elements being joined to said collectors and all the said elements of a given set having their ends arranged in one or the other of two groups and in different planes parallel to the smoke tube rows the ends of said two groups being bent oppositely but parallel to the plane of the flue tube rows, as and for the purpose described. 80

3. A smoke tube superheater comprising, 85 in combination, a boiler provided with parallel rows of smoke tubes, sets of superheater elements at least three to a set arranged in rows corresponding to smoke tube rows, and steam collectors for saturated and superheated steam respectively, the ends of 90 the superheater elements being joined to said collectors and all the said elements of a given set having their ends arranged in one or the other of two groups said ends of 95 said two groups being bent to lie in different planes parallel to the smoke tube rows, thereby lying side by side as they enter the steam collectors, and connecting means extending between adjacent ends in 100 different planes for uniting said ends to the steam collectors.

4. A smoke tube superheater comprising, 105 in combination, a boiler provided with parallel rows of smoke tubes, sets of superheater elements at least three to a set arranged in rows corresponding to smoke tube rows, and steam collectors for saturated and superheated steam respectively, the ends of 110 the superheater elements being joined to said collectors and all the said elements of a given set having their ends arranged in one or the other of two groups the ends of all of said groups being bent to lie in different planes parallel to the smoke tube rows thereby lying side by side as they enter the steam collectors, there being at least twice as many planes for the element ends as there are 115 rows of smoke tubes, and connecting members perpendicular to said planes, extending between adjacent ends in different planes for uniting said ends to the steam collectors.

5. A smoke tube superheater comprising, 120 in combination, a boiler provided with parallel rows of smoke tubes, sets of superheater elements at least three to a set arranged in rows corresponding to smoke tube rows, and steam collectors for saturated and superheated steam respectively, the ends of 125 130

4
the superheater elements being joined to said collectors and all the said elements of a given set having their ends arranged in one or the other of two groups the ends of all of said 5 groups being bent to lie in different planes parallel to the smoke tube rows thereby lying side by side as they enter the steam collectors, there being at least twice as many planes for the element ends as there are rows 10 of smoke tubes, and connecting members

perpendicular to said planes and having central bolts going into the steam collector.

In testimony whereof, I have hereunto set my hand in the presence of two subscribing witnesses.

PETER THOMSEN.
